UNITED STATES PATENT OFFICE.

GILBERT S. PEASE, OF RICHFIELD, WISCONSIN.

MODULATING DEVICE FOR SOUND-REPRODUCERS.

1,388,753.

Specification of Letters Patent. Patented Aug. 23, 1921.

Application filed March 9, 1920. Serial No. 364,447.

To all whom it may concern:

Be it known that I, GILBERT S. PEASE, a citizen of the United States, and a resident of Richfield, in the county of Adams and State of Wisconsin, have invented a new and Improved Modulating Device for Sound-Reproducers, of which the following is a full, clear, and exact description.

The invention relates to phonographs and similar sound reproducing machines, and its object is to provide a new and improved modulating device for sound reproducers arranged to enable an operator to vary the vibratory action of the diaphragm at will and with a view to render the sounds either softer or louder as desired.

Another object is to permit of conveniently attaching the modulating device to sound reproducers as now generally constructed.

Another object is to provide a modulating device which is exceedingly simple in construction, cheap to manufacture and easy to apply to the sound box.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in both views.

Figure 1 is a face view of the improved modulating device as applied to a sound reproducer of the diaphragm type; and

Fig. 2 is a transverse section of the same on the line 2--2 of Fig. 1.

In the box 10 of usual construction is mounted a diaphragm 11 connected at its center with the lever 12 carrying the stylus 13 adapted to engage the usual sound groove in a record 14. The rear face of the diaphragm 11 is engaged by a modulating member 20 in the form of a piece of rubber tubing mounted on a wire 21 of segmental shape and terminating in a pivot 22 journaled in the back of the sound box 10, as plainly shown in the drawings. The outer end of the pivot 22 terminates in a handle 23 un-

der the control of the user of the phonograph to permit of swinging the modulating member 20 nearer to or farther from the center of the diaphragm 11. By reference to Fig. 2 it will be noticed that the modulating member 20 is interposed between the face of the sound box 10 and the back of the diaphragm 11, and this modulating member 20 and its supporting wire 21 are preferably made segmental, as indicated in Fig. 1, so that when the modulating member is in its outermost position it is concentric with the rim of the sound box 10 and the peripheral edge of the diaphragm 11.

On swinging the modulating member 20 nearer the center, as indicated in dotted lines in Fig. 1, the vibratory motion of the diaphragm 11 is reduced and consequently a softer tone is reproduced. It is understood that by the arrangement described the user can readily move the modulating member 20 into any desired intermediate position from the outermost normal to an innermost position to modulate the reproduction of the sounds correspondingly.

Having thus described my invention, I claim as new and desire to secure by Letters Patent:—

1. In a sound reproducer, a sound box provided with a diaphragm, a segmental modulating member interposed between the sound box and the rear face of the diaphragm and engaging the latter throughout its length, a pivot carrying the said member and journaled in the said sound box, and a handle on the outer end of the said pivot to permit of moving the said modulating member nearer to or farther from the center of the diaphragm.

2. In a sound reproducer, the combination with a sound box provided with a diaphragm, of a modulating device interposed between the sound box and the rear face of the diaphragm, said device consisting of a segmental member engaging the diaphragm throughout its length, said member having an integral pivot by which it is mounted in the rear face of the sound box and from which extends an integral handle.

GILBERT S. PEASE.
